PUMP TYPE DISPENSER WITH CARTRIDGE
HAVING FLEXIBLE AND RIGID PORTIONS

Joseph R. Harrison, Jr., Chicago, Ill.

Application March 31, 1947, Serial No. 738,288

11 Claims. (Cl. 222—95)

1

My invention relates, generally, to dispensing means, and it has particular relation to dispensers for tooth paste, shaving cream and like material.

Among the objects of my invention are: to provide a holder for a renewable cartridge or refill unit containing the material to be dispensed; to employ air pressure developed by squeezing a part of the holder for ejecting the material from the cartridge; to employ a self restoring rubber bulb as a part of the holder and to provide a valve therein for trapping air between the same and the cartridge; to provide the cartridge with a rigid tubular section and a member that is movable therethrough on application of air pressure thereto for ejecting the material; to form the movable member of flexible material having a length about equal to that of the rigid tubular section; to reinforce the movable member of flexible material; and to employ a plunger within the rigid tubular section for ejecting the material therefrom.

With the foregoing objects outlined and with other objects in view which will appear as the description proceeds, my invention consists in the novel features hereinafter described in detail, illustrated in the accompanying drawings, and more particularly pointed out in the appended claims.

In the drawings:

Fig. 1 is a view, in side elevation, of a dispenser constructed in accordance with my invention;

Fig. 2 is a bottom plan view of the dispenser;

Fig. 3 is a longitudinal sectional view of the dispenser, showing one form of cartridge or refill unit in the holder;

Fig. 4 is a longitudinal sectional view of the cartridge when it has been emptied;

Fig. 5 is a view, partly in side elevation, and partly in section, of a modified form of cartridge;

Figs. 6 and 7 show modified forms of cartridge in which different reinforcing means for the flexible member thereof are provided; and

Fig. 8 is a detail sectional view, at an enlarged scale, of the air valve for the bulb of the holder.

Referring now to Figs. 1, 2 and 3 of the drawings, the reference character 10 designates, generally, a dispenser which includes a reusable holder that is indicated, generally, at 11. As indicated, the holder 11 is intended to be reused and to contain a cartridge or refill unit, to be described in detail hereinafter, which contains the material, such as tooth paste, shaving cream, etc. to be dispensed in small quantities.

The holder 11 may have at its upper end a large threaded cap 12, preferably of metal, which

2

is removed to permit insertion of the cartridge. The cap 12 has a smaller threaded cap 13, of plastic or like material, which can be removed to permit ejection of the material from the cartridge and then replaced. The holder 11 includes a rigid tubular shell 14 of metal or plastic to the lower end of which a deformable member or bulb 15 of rubber or the like may be secured by any suitable means, such as the ribs 16. The bulb 15 can be squeezed by the hand to generate air pressure within the holder 11.

The bulb 15 has an integrally formed suction cup 17 at its lower end which, when depressed against a flat surface, serves to create a vacuum and thereby to hold the dispenser 10 in an upright position relative to the flat surface.

At its lower end, the bulb 15 has an integrally formed flange 18 in which a valve mechanism, shown generally at 19, is located, and illustrated more clearly in Fig. 8. The valve mechanism 19 includes a valve stem 20 that projects through the flange 18 and has a radial foot portion 21 which, together with a retaining ring 22, serves to hold the valve mechanism in place. The valve stem 20 has a longitudinal aperture 23, the upper end of which is automatically closed by a ball 24 that is movable in a cavity 25, the upper walls of which are turned inwardly, as shown at 26, to prevent the same from escaping.

Within the holder 11 is a cartridge or refill unit that is indicated, generally, at 30 in Figs. 3 and 4. It will be understood that it is suitable for holding cream-like, or jelly-like material that is to be dispensed in small quantities. It includes

a rigid tubular member 31 that may be formed of metal, cardboard, plastic or the like, and which may have an out-turned flange 32 which bears against the upper end of the shell 14. A closure member 33 in the form of an annular disc is secured, as by adhesive, to the flange 32 for closing the upper end of the tubular member 31. The closure member 33 has an aperture 34 which registers with an aperture 35 in the cap 12, through which the material is ejected when the cap 13 is removed. The closure member 33 preferably has a removable cover secured thereto for shipping and storing purposes which can be stripped off easily when the cartridge 30 is inserted in the holder 11.

At its lower end, the tubular member 31 has a flexible member 36 secured thereto. It may overlap the member 31, as shown at 37, and may be formed of suitable material such as water-proofed cloth or like fabric, or polythene or acetate plastic sheeting or cellophane. When the cartridge or

refill unit 30 is first placed in the holder 11, the flexible member 36, the length of which is about equal to that of the tubular member 31, extends full length into the bulb 15, as shown in Fig. 3. When the bulb 15 is squeezed, the pressure of the air between it and the cartridge 30 is increased. Since only the member 36 is deformable, the air pressure applied to it causes the same to collapse and then, on repeated squeezings of the bulb 15, to assume the shape shown in Fig. 4. In so doing, the material within the cartridge 30 is dispensed through the aperture 35 in the cap 12.

A gasket 38, of soft rubber or the like, may be positioned underneath the cap 12 for providing an air-tight seal with the shell 14.

In Fig. 5, an alternate form of cartridge is shown, generally at 40. It may comprise a rigid sleeve 41 of metal, paper, plastic or the like, which can be inserted in the holder 11 when its cap 12 is removed. It may extend nearly to the lower end of the bulb 15, and at its upper end it may have a flange 42 for abutting the upper end of the shell 14, and to which may be secured an annular closure member 43. At the lower end of the sleeve 41, there is positioned, when the cartridge 40 is full, a plunger 44 that is gradually driven to the upper end by the repeated application of air pressure thereto.

Another form of cartridge is shown generally at 30' in Fig. 6. It is essentially of the same construction as illustrated in Figs. 3 and 4, with the addition of reinforcing means in the form of oppositely spirally wound strips 47 and 48 of relatively rigid material such as card board, fish paper or the like. These strips serve to reduce the likelihood of rupture of the flexible member 36, and collapse therewith on application of air pressure thereto as described.

Another cartridge construction is shown at 30" in Fig. 7. It is similar to the cartridge 30, but for reinforcing means, there may be provided a sleeve 50 of rigid material, such as card board or fish paper, which telescopes with the rigid tubular member 31 as the flexible member 35 is collapsed. Like the strips 47 and 48, the sleeve 50 serves to reduce the likelihood of the flexible member 36 being ruptured on application of air pressure thereto.

While I have disclosed what I consider to be preferred embodiments of my invention in such manner that the same may be readily understood by those skilled in the art, I am aware that changes may be made in the details disclosed, without departing from the spirit of the invention, as expressed in the following claims.

What I claim and desire to secure by Letters Patent is:

1. A dispenser for tooth paste, shaving cream and like material, comprising, in combination; a holder including a rigid tubular shell, and a collapsible bulb secured to one end thereof; and a tubular cartridge insertable in said holder and removable therefrom, including a rigid tubular member co-axial with said shell for receiving said material; and flexible means extending from and movable relative to said rigid tubular member for ejecting said material therefrom; said holder forming an air-tight enclosure for said cartridge and trapping a quantity of air therebetween whereby, when said bulb is squeezed, the resulting air pressure applied to said movable means operates the same as aforesaid.

2. The invention, as set forth in claim 1, where-

in the collapsible bulb has an air valve operable on release of pressure from the former to admit air to fill the space previously occupied by the ejected material.

3. The invention, as set forth in claim 2, wherein in the bulb is formed of self restoring resilient material whereby after it has been squeezed and released it restores itself to its initial form.

4. The invention, as set forth in claim 3, wherein in the bulb has a suction cup integrally formed therewith which serves to hold the dispenser in predetermined relation to a flat surface when said suction cup is applied thereto.

5. The invention, as set forth in claim 1, wherein in the movable means is a plunger which is movable through the rigid tubular member for displacing the material on application of air pressure.

6. A dispenser for tooth paste, shaving cream and like material, comprising, in combination; a holder including a rigid tubular shell, and a deformable member secured thereto; and a cartridge insertable in said holder and including a rigid tubular member coextensive with said shell, and a flexible member secured thereto and extending therefrom to form therewith a container for said material; said deformable member when squeezed acting to collapse said flexible member for ejecting said material from said cartridge, said flexible member being about the same length as said rigid tubular member and adapted to telescope with the same to eject substantially all of said material therefrom.

7. The invention, as set forth in claim 6, wherein in the deformable member is a self restoring rubber bulb.

8. The invention, as set forth in claim 6, wherein in there are reinforcing means located within the flexible member for reducing the likelihood of the same being ruptured when the deformable member is squeezed.

9. The invention, as set forth in claim 8, wherein in the reinforcing means comprises a rigid sleeve telescopically related to the rigid tubular member and coextensive with the flexible member when the cartridge is unused.

10. The invention, as set forth in claim 8, wherein the reinforcing means is collapsible within the flexible member.

11. The invention, as set forth in claim 8, wherein the reinforcing means comprises a pair of interfitting oppositely spirally wound rigid strips.

JOSEPH R. HARRISON, JR.
